THREE-DIMENSIONAL ARTICLE FORMED OF
SHEET MATERIAL

William Wolfson, Sunnyside, Long Island, N. Y.

Application March 7, 1938, Serial No. 194,279

18 Claims.

(Cl. 40—126)

This invention relates to articles or structures of the class of advertising displays, greeting cards, place cards, children's toys and the like. It relates more particularly to articles or structures of the said type produced from sheet material such as pasteboard, sheet metal, plastic materials (such as Celluloid), and the like, adapted to be supplied to the user in a compact, knocked-down, flat (substantially two-dimensional) form and erected by the user into three-dimensional form.

In certain of its aspects the present invention is an improvement in the articles or structures forming the subject matter of my application Serial No. 50,685, filed November 20, 1935.

An object of the invention is to provide an article of the class described, which is adapted to be supplied in a compact, flat form, preferably as a single piece or unit, and which can be readily erected to form a three-dimensional display, card or toy without requiring any special skill or additional materials and without requiring any substantial expenditure of time or effort. A further object of the invention is to provide a device of the class described which is adapted to be supplied in a compact, flat form for shipment or storage, preferably as a single piece or unit, in which a maximum sculptural effect is secured when the device is erected, without requiring any substantial expenditure of time or effort in erecting the device. Other objects of the invention are to provide a device of the class described which is simple and cheap to manufacture, and to provide a device of the class described which is adapted to be made from a single, flat sheet of stiff paper or other stiff sheet material yieldingly providing resistance to bending. Additional objects of the invention are to provide devices of the class described in which the printing required for the pictorial representations included in the device may be accomplished on one side of a single flat sheet of material, such as stiff paper; and to provide means whereby the erection of the device into a three-dimensional form and for collapsing the device into a substantially two-dimensional flat form may be readily accomplished.

Other objects of the invention will in part be obvious and will in part appear hereinafter.

The invention will be described in connection with the accompanying drawings, in which only a few of the many possible embodiments are shown for purposes of illustration.

In the drawings, Fig. 1 is a perspective view of one embodiment of the invention in erected

form adapted for use as a display, toy or the like;

Fig. 2 is a side elevation of the same embodiment in the erected form;

Fig. 3 is a front elevation of the same embodiment in the collapsed, flat form adapted for shipment, storage, or the like;

Fig. 4 is a rear elevation of the same embodiment in collapsed, flat form;

Fig. 5 is a top view of the same embodiment in the collapsed, flat form shown in Figs. 3 and 4;

Fig. 6 is a top view of the same embodiment in the erected form shown in Fig. 1;

Fig. 7 is a plan view of a blank for forming the embodiment shown in Figs. 1 to 6;

Fig. 8 is a perspective view of another embodiment of the invention in erected form adapted for use as a display, toy, or the like; and

Fig. 9 is a plan view of a blank for forming the embodiment of Fig. 8.

Referring to the embodiment shown in Figs. 1 to 7 for purposes of illustration, the device consists of a body member 1 and wing members 2 and 3 hingedly connected at joints 5 and 6, respectively, to the body member at opposite sides thereof and adapted to overlap when folded in operative form. The body and wing members are formed by scoring and creasing or folding a single sheet of stiff, resilient sheet material of suitable thickness (such as stiff paper, bristol board or other suitable material herein referred to) that has been stamped or cut as shown in Fig. 7, to provide elements hereinafter referred to as well as a contour in accordance with the representation desired. It will be observed that, while the body member 1 is normally flat when the article is in collapsed form for shipment or storage, it is adapted to be bowed or arched, as shown in Fig. 6 (or otherwise bent into three-dimensional form) when erected for use as a display or the like.

To maintain the body member 1 in bent position when erected, means are provided on one of the wing members for cooperation with the body member. As shown in the specific embodiment of Figs. 1 to 7, such a locking means is formed by providing the body member 1 with a slot 8, and providing wing member 3 with a tab 9 adapted to fit within the slot 8 and having a notch 7 formed therein for cooperating with the body member 1 at the end 11 of the slot 8. Preferably the tab 9 on the wing member 3 is of such proportions that when the device is in assembled relation the tab 9 lies within the slot 8, both when the device is in the collapsed and the erected

forms, thereby rendering the device more fool-proof. Further, the distance between the notch 7 and joint or fold 6 is less than the distance between the slot 8 and the joint or fold 6, so that 5 when the notch 7 is locked over the body member at the edge 11 of the slot 8, the body member 1 is held bent in three-dimensional form. Preferably the body member 1 is formed of resilient material so that when in bent form it is under 10 tension, but it is not essential that the device be constructed of resilient material. As will be evident to those skilled in the art, the body member 1 may be scored to bend into three-dimensional form without being under tension. Further, it is not essential that the device be locked 15 in the erected or bent form, particularly in connection with its use as a toy.

For the purpose of providing additional three-dimensional effect the wing member 3 is provided 20 with a slot-like opening 24 and the wing member 2 is provided with a tab 25 adapted to fit into the opening 24 when in operative relation. The relation of the edge 26 of the wing 2 to the joint or fold 5 and the location of opening 24 with 25 respect to the joint or fold 6 are such that when the body member 1 is bent into three-dimensional form and the distance between the folds 5 and 6 is hereby decreased, the wing member 2 is caused to bulge into a three-dimensional form by the 30 shortening of the distance between the edge 26 and joint or fold 5 resulting therefrom. Preferably the tab 25 is of such dimensions that when inserted in the opening 24 it remains therein when the device is in the collapsed, flat form.

35 With a view to further enhancing the three-dimensional effect of the device, the wing member 2 is cut along line 39, thereby providing an additional free element 40. As a result, when the wing member 2 is bent into three-dimensional form, the element 40 being free to move out of the plane of the device in the collapsed form, assumes a position spaced from the wing member 3.

An additional wing member 12 hingedly connected to the wing member 3 at the joint 13 (and 45 as shown in the embodiment illustrated in Figs. 1 to 7, formed by cutting the wing member 3 along the line 15) is provided to supplement the three-dimensional effect of the device when erected and for other purposes, as will appear more fully hereinafter. The wing member 12 is cut away at its 50 upper edge to provide a notch 14, and the wing member 2 is cut away at its lower edge to provide a notch 16. The location of the notches 14 and 16 with respect to the joints 14 and 5 are such that when the wings 2, 3 and 12 are folded over the body member 1 in overlapping relation and the device is in the collapsed or flat form, the wings 2 and 12 interlock within the notches 14 and 16. As a result, when the body member 1 is 55 bent into three-dimensional form and the distance between the edges 5 and 6 of the body member is thereby shortened, the wing member 12 is caused to bend into a three-dimensional form by the pressure exerted by the wing member 2 60 through the notches 16 and 14.

The wing member 12 is further provided with a tab 39 adapted to be bent back along the line 31, thereby forming a flap rearwardly of the wing member 12 when in operative relation. Preferably wing member 2 is provided with a projection 32 abutting the tab 30 when in operative relation, thereby providing a pocket for the insertion of matter to be dispensed, as for example, advertising matter shown as 45 in Fig. 1.

75 To further enhance the three-dimensional ef-

fect, additional wing members 18 and 33 are provided, respectively hinged to the body member 1 at the joints or folds 19 and 34.

Wing member 18 is cut along the line 21 to provide a free member 22. When assembled in operative relation, wing member 18 projects between the body member 1 and wing member 3, but the wing member 3 lies between the wing member 18 and free member 22. As a result, when the body member 1 is bent into three-dimensional form the joint 19 is moved away from the plane of wing member 3 and as a result member 22 is moved into three-dimensional angular relation to the wing member 3.

The wing member 33 is provided with a tab 35, similar to the tab 25 on wing member 2; and wing member 3 is provided with an opening 36 adapted to receive the tab 35 when the wings are overlapped over the body member 1 in operative relation. As in the case of wing member 2, the distance between the edge 37 of the wing member 33 and joint 34 and the location of the slot-like opening 36 are such that the tab 35 lies within the opening 36, both when the device is in collapsed and in erected forms, and the wing member 33 assumes a three-dimensional form, when the body member 1 is bent in three-dimensional form, due to decrease in distance between edge 37 and joint 34.

In assembling the device shown in blank or development in Fig. 7 into operative relation, the wing member 3 is folded over the body member and the tab 9 is inserted in the slot 8. The wing 18 is then bent over the body member 1, so as to lie between the body member 1 and wing member 3, the wing member 3 lying between wing member 18 and element 22. Wing member 2 is then folded over wing member 3 and under wing member 12, and tab 25 is inserted in the opening 24. The tab 30 is folded back so as to lie between projection 32 and wing member 12, and the notches 14 and 16 are then interengaged. Wing member 33 is then folded to overlap wing member 12 and tab 35 is inserted in opening 36.

In erecting the device for use, the body member 1 is flexed or bent, as by applying pressure simultaneously at the edges 5 and 6, to cause tab 9 to slide within the slot 6 at least to the point where shoulder 10 projects beyond the slot 8, whereby the body member 1 fits within the notch 7 and is locked thereby in bent form.

To facilitate opening and closing of the device the body member 1 is provided with one or more openings adapted to receive a finger or fingers of the operator using the device.

In the preferred embodiment of the invention, as shown in Fig. 4, the body member is formed with a single opening 41 located at a distance from the slot 8 and in the direction opposite to the edge of the tab 9 in which the notch 7 is located. Thus, with the notch 7 located on the lower edge of the tab 9, as shown in the embodiment illustrated in Figs. 1 to 7, the opening 41 is located above the level of the edge 11 of the slot 8. As a result of this arrangement, when the tab 9 is grasped with one hand by the operator and a finger of the other hand is inserted in the opening 41 and the tab 9 is pulled in a direction out of the slot 8, the force exerted is in the direction of line A—A of Fig. 4, with the result that the tab 9 is forced downward. Consequently, when the notch 7 is reached, the tab 9 is forced downward over the body member at the edge 11 and the body member is locked in bent position.

By this arrangement the erection of the device into three-dimensional form is greatly facilitated.

For the purpose of facilitating the collapse or closing of the device into flat form, an opening

5. 42 is similarly provided in the body member 1. Since the desired result is an application of force in the direction of line B—B of Fig. 4, thereby tending to lift the notch 7 out of engagement with the body member at the point 11, the opening 42 is located below the level of the edge 11. In collapsing the device, the tab 9 is grasped by one hand, a finger of the other hand of the operator is inserted in opening 42 and the tab 9 is pulled until the notch 7 is freed from engagement 15 with the body member at the point 11 and the device is then permitted to collapse. In the preferred embodiment of the invention the body member 1 is formed of resilient stiff material providing sufficient tension to cause the body member to tend to assume the relatively two-dimensional, flat position.

It will be observed that, by reason of the cut 39 and the stiffness of the material, the portion 40 of the wing member 2 does not bend when 25 wing member 2 is bent or arched, but remains straight, thereby providing an element of the erected device in a plane spaced from the wing member 3. Further, the cooperating action of the wings 2, 3, 12 and 33 causes the wings 2, 12 30 and 33 to bend or arch into three-dimensional form upon bending of the body member 1 into a three-dimensional form. By having the distance between the edge 26 and joint or fold 5 different from the distance between the edge 37 35 and joint or fold 34 (and corresponding different spacing of the openings 24 and 36 relative to the joint or fold 6), the spacing of the wings 2 and 33 relative to the wing 3, and the shape assumed by said wings, when the device is erected into 40 three-dimensional form, are different, thereby further enhancing the three-dimensional effect. It will also be noted that the positions assumed by the wing members upon erection of the device are predetermined and automatically assumed by reason of the construction. Further, 45 it will be observed that by reason of the bending of the body member 1 and resultant bending of the wing members 12 and 33 in an opposite direction to the bending of the body member 1, as a 50 result of the interposition of the wing member 3 between them, the lower edges of the device in the erected form cover a substantial area, thereby making the device relatively stable and not requiring the provision of additional standing 55 means.

It will thus be apparent that the structure provides means whereby flexing or bending of the body member from a flat (unreacted) position automatically projects additional elements 60 from the plane of the flat (unreacted) device, with the result that a flat, substantially uniplanar assembly is automatically converted into a three-dimensional device having a plurality of planes spaced from each other.

65 As above noted, the body member and wing members may be formed with an outline of suitable contour to represent any desired figure or pictorial representation. Further, the body member and/or the wing members may carry 70 pictorial matter and/or advertising matter, as desired. In the preferred embodiment of the present invention, the body member 1 forms the background for the wing members and is preferably concealed by said wing members when pictorial representations, greeting, advertising mat-

ter, etc. are carried by the device. As a result, the necessary printing and color work can be applied to only one side of the blank, thereby greatly reducing the cost of the article.

The embodiment shown in Figs. 8 and 9 similarly includes the structural features described in connection with the embodiment shown in Figs. 1 to 7. Thus it consists of a body member 101 and wing members 102 and 103 hingedly connected at joints 105 and 106, respectively, to the 10 body member at opposite sides thereof and adapted to overlap when folded in operative relation, which are formed by the scoring and creasing or folding a single sheet of stiff, resilient sheet material of suitable thickness that has been 15 stamped or cut as shown in Fig. 9. The body member 101 is provided with an opening 108, and wing member 103 is provided with a tab 109 adapted to fit within the opening 108 and has a notch 107 formed therein for cooperating with 20 the body member at the end 111 of the opening 108. Preferably the tab 109 is of such proportions that when the device is in assembled relation the tab 109 lies within the opening 108, both when the device is in collapsed and in the erected 25 forms.

For the purpose of providing additional three-dimensional effect, the wing member 103 is provided with a slot-like opening 124, and the wing member 102 is provided with a tab 125 adapted 30 to fit into the opening 124 when in operative relation. Preferably the tab 125 is of such dimensions that when inserted in the opening 124 it remains therein when the device is in the collapsed, flat form.

As in the case of the embodiment shown in Figs. 1 to 7, the dimensions of the wing members 102 and 103 and the location of the openings 108 and 124, notch 107 and tab 125 are such that the body member 101 is held bent in three-dimensional form by the locking of the notch 107 40 over the body member at the edge 111 of the opening 108, and the wing member 102 is bent into three-dimensional form when the body member 1 is bent into three-dimensional form. 45 It is noted that wing member 102 is scored along the line 143 to provide an angular form when the wing member 102 is bent into three-dimensional form.

With a view to increasing the sculptural effect, the device is provided with additional wing members 133 and 153 which are provided with tabs 135 and 155 adapted to be inserted, respectively, in the openings 136 and 156, formed in the wing member 103. Further, a wing member 118 55 formed on the body member and adapted to lie within the cut-out portion 123 of the wing member 103 is provided. Increased sculptural effect is secured, according to a feature of the present invention, by cutting an opening or slot 138 in 60 the wing member 102 to receive the wing 118. Similarly to the embodiment shown in Figs. 1 and 7, the body member 101 is provided with openings 141 and 142 for facilitating erection and collapsing of the device.

The invention is not limited to the details of construction and the features hereinabove described in connection with the specific embodiments shown in Figs. 1 to 9. While it is advantageous from the standpoint of cheapness, ease 70 of construction and simplicity of manufacture to form the device from a single piece of sheet material by cutting and/or stamping and folding, with or without scoring, it will be evident to those familiar with the manufacture of such devices 75

that the body member and one or more of the wing members may be formed of separate pieces of sheet material and suitably jointed to provide hinged wing members. It will be further noted 5 that only the body member and the wing members which bend need be formed of resilient stiff material. The latter form of construction (jointed separate pieces) is preferably employed when making the article from material which does not 10 hinge readily when folded.

It is further to be noted, while a device having all of the advantageous features of the embodiments shown in Figs. 1 to 9 represents a preferred form of the invention, the invention 15 is capable of embodiment in forms omitting one or more of said features.

Obviously, additional wing members may be hinged to the body member and/or the wing members. The advantageous three-dimensional 20 effect secured by having the wing 118 project through an opening in the wing member 138 also may be secured or supplemented by other wing members carried by the body member or carried by other wing members, projecting through openings 25 formed in other wing members. Further, the angles assumed by the wing members may vary. It is noted, however, that the wing member 3 in the erected position takes the position of a cord of a circle with respect to an arc 30 formed by the arched body member.

It will be understood that the invention is not limited to any particular arrangement or size of the various members with respect to each other. Thus, the slot and shoulder locking means 35 shown at 8 and 10 in the drawings may be placed on the opposite side by reversing the location of the wing members 2 and 3.

Instead of holding the body member 1 is bent 40 form by means of the interlocking action of shoulder 10 of tab 9 and slot 8, the device may be locked in bent form by other means; for example, in the manner shown in my application Ser. No. 50,685. It is noted locking means provided by tab adds to the pictorial and three-dimensional 45 effect as well as serving as a locking member.

The devices of the present invention can be employed for a number of useful purposes. Thus, they can be employed as advertising displays, place cards, greeting cards, children's toys 50 and other amusement devices, for commercial, educational and decorative purposes, etc. Inasmuch as they may be supplied to the user in the form of a single unit which can be readily erected to form a pleasing three-dimensional structure, 55 without requiring assembling of separate parts, intricate instructions to the user, skill in assembling, or additional material, they are admirably suited for such purposes.

They also present numerous advantages from 60 the standpoint of their manufacture; for example, they can be produced from a single sheet of material merely by cutting and/or stamping and folding, thereby avoiding assembling of separate parts; although as above noted, if desired, 65 they can be made from separate sections of sheet material suitably joined to form a hinged structure of the type herein described.

This application is a continuation-in-part of my application Serial No. 50,685, filed November 70 20, 1935.

I claim:

1. An article of the character described comprising a normally flat body member adapted to be bent into a three-dimensional form, wing 75 members overlapping the body member, one of

said wing members being hingedly connected near one of its edges to the body member and being interconnected near another of its edges with another of said wing members to cause a portion of the first mentioned wing member intermediate said edges to move into a three-dimensional form when the body member is bent into three-dimensional form. 5

2. An article of the character described comprising a normally flat body member adapted to 10 be bent into a three-dimensional form, wing members overlapping the body member, one of said wing members being hingedly connected near one of its edges to the body member and being interconnected near another of its edges 15 with another of said wing members to cause a portion of the first mentioned wing member intermediate said edges to move into three-dimensional relation to said other wing member when the body member is bent into three-dimensional 20 form.

3. An article of the character described comprising a normally flat body member formed of resilient, stiff material, adapted to be bent into 25 a three-dimensional form, wing members overlapping the body member, one of said wing members being hingedly connected near one of its edges to the body member and being interconnected near another of its edges with another of said wing members to cause a portion of the first 30 mentioned wing member intermediate said edges to bulge away from said body member when the body member is bent into three-dimensional form.

4. An article of the character described comprising a normally flat body member, formed of stiff sheet material, adapted to be bent into three-dimensional form, a plurality of wing members overlapping the body member, one of said wing members having means for engaging the body 40 member for holding the body member in bent form, another wing member hingedly connected to the body member and having engagement with said first mentioned wing member to cause a portion of the second mentioned wing member 45 intermediate its edges to move into a three-dimensional form when the body member is bent into three-dimensional form.

5. An article of the character described comprising a normally flat body member adapted to 50 be bent into a three-dimensional form, a wing member overlapping the body member and hingedly connected near one of its edges to the body member, and means near another of the edges of said wing member for causing a portion 55 of said wing member intermediate its edges to move into a three-dimensional form when the body member bends into three-dimensional form, said means including a connection for causing said edges of the wing member to move 60 toward each other as a result of bending of the body member into three-dimensional form.

6. An article of the character described comprising a normally flat body member adapted to 65 be bent into a three-dimensional form and having two edges which move toward and away from each other when the body member is bent into three-dimensional form and collapsed, respectively, two wing members overlapping the body 70 member and hingedly connected to said body member at said edges, and means on one of said wing members to cause the edges of the other wing member to move toward and away from each other when the body member is bent into 75

three-dimensional form and collapsed, respectively.

7. An article of the character described comprising a normally flat body member adapted to be bent into a three-dimensional form and having two edges which move toward and away from each other when the body member is bent into three-dimensional form and collapsed, respectively, a wing member overlapping the body member and hingedly connected near one of its edges to the body member near one of said edges thereof, and means near another edge of said wing member for causing said edges to move toward and away from each other, respectively, when said body member is bent into three-dimensional form and collapsed, thereby causing a portion of the wing member intermediate its edges to move into a three-dimensional form when the body member is bent into three-dimensional form, said means including a connection with said other edge of said body member.

8. An article of the character described comprising a normally flat body member adapted to be bent into a three-dimensional form and wing members overlapping the body member, said article having an opening therein, one of said wing members having a projection passing through said opening, another of said wing members being hingedly connected near one of its edges to the body member, and means connecting the latter wing member near a free edge thereof with the first mentioned wing member to cause the second mentioned wing member intermediate its edges to move into three-dimensional relation to said body member when the body member is bent into three-dimensional form.

9. An article of the character described comprising a normally flat body member adapted to be bent into a three-dimensional form and having two edges which move toward and away from each other when the body member is bent into three-dimensional form and collapsed, respectively, said body member having an opening therein, a wing member overlapping the body member and hingedly connected near one of its edges to the body member near one of said edges thereof, and means near another edge of said wing member for causing said edges to move toward and away from each other, respectively, when said body member is bent into three-dimensional form and collapsed, thereby causing a portion of the wing member intermediate its edges to move into a three-dimensional form when the body member is bent into three-dimensional form, said means including another wing member hingedly connected to said body member and having a portion thereof passing through said opening in the body member, and means for interconnecting said wing.

10. An article of the character described adapted when collapsed to lie flat and when erected to form a three-dimensional structure comprising a normally flat body member, formed of stiff sheet material, adapted to be bent into three-dimensional form, and a plurality of wing members overlapping the body member, one of said wing members having means for holding the body member in bent form and being formed with an opening therein near its junction with the body member, another wing member hingedly connected to the body member and having engagement with said first mentioned wing member at said opening to cause a portion of the second mentioned wing member intermediate its edges

to move into a three-dimensional form when the body member bends into three-dimensional form.

11. An article of the character described adapted when collapsed to lie flat and when erected to form a three-dimensional structure comprising a normally flat body member, formed of stiff sheet material, adapted to be bent into three-dimensional form and having an opening formed therein, a lateral wing member overlapping said body member when in collapsed position and having a member adapted to lie in said opening when said body member is in collapsed position, said wing member having an opening therein, and another lateral wing member overlapping said first mentioned wing member when in collapsed position and having a projection formed thereon adapted to lie within the opening in the first mentioned wing member whereby the second mentioned wing member is caused to bulge away from the body member into a three-dimensional form when the body member is bent into a three-dimensional form.

12. An article of the character described adapted when collapsed to lie flat and when erected to form a three-dimensional structure, comprising a normally flat body member, formed of stiff sheet material, adapted to be bent into three-dimensional form, a lateral wing member overlapping said body member when in collapsed position, another lateral wing member overlapping said first mentioned wing member when in collapsed position and having means for interconnecting said wing members to cause the second mentioned wing member to bulge away from the body member into a three-dimensional form when the body member bends into a three-dimensional form, an additional wing member overlapping said body member when in collapsed position and having engagement with one of the other wing members whereby the additional wing member is moved into a predetermined plane at an angle to the first mentioned wing member when the body member is bent into a three-dimensional form.

13. A display card, toy or the like adapted when collapsed to lie flat and when erected to form a self-sustaining three-dimensional structure and formed of a single sheet of stiff, resilient sheet material of the character of resilient pasteboard or the like by cutting and folding, comprising a central body portion having an opening formed therein, a lateral wing portion overlapping said central portion when in collapsed position and having a member adapted to lie in said opening when said central portion is in collapsed position and having a projection adapted to engage the central portion when the latter is in bent position, said wing portion having an opening therein, another lateral wing portion overlapping said first mentioned wing portion when in collapsed position and having a projection formed thereon adapted to lie within the opening in the first mentioned wing portion whereby the second mentioned wing portion is caused to bulge away from the central body portion into a three-dimensional form when the body portion is bent into a three-dimensional form.

14. A display card, toy or the like adapted when collapsed to lie flat and when erected to form a self-sustaining three-dimensional structure and formed of a single sheet of stiff, resilient sheet material of the character of resilient pasteboard or the like by cutting and folding, comprising a central body portion hav-

- ing an opening formed therein, a lateral wing portion overlapping said central portion when in collapsed position and having a member adapted to lie in said opening when said central portion is 5 in collapsed position and having a projection adapted to engage the central portion when the latter is in bent position, said wing portion having an opening therein, another lateral wing portion overlapping said first mentioned wing portion when in collapsed position and having a projection formed thereon adapted to lie within the opening in the first mentioned wing portion whereby the second mentioned wing portion is caused to bulge away from the central body portion 10 into a three-dimensional form when the body portion is bent into a three-dimensional form, an additional wing portion overlapping said central portion when in collapsed position and having engagement with one of the other wing 15 portions whereby the additional wing portion is moved into a predetermined plane at an angle to the first mentioned wing portion when the body portion is bent into a three-dimensional form.
15. A display card, toy or the like adapted when collapsed to lie flat and when erected to form a self-sustaining three-dimensional structure and formed of a single sheet of stiff, resilient sheet material of the character of resilient pasteboard or the like by cutting and folding, 20 comprising a central body portion having an opening formed therein, a lateral wing portion overlapping the central portion when in collapsed position and having a member adapted to lie in said opening when said central portion is in collapsed position and having a projection adapted to engage the central portion when the latter is in bent position, said wing portion having an 25 opening therein, another lateral wing portion overlapping said first mentioned wing portion when in collapsed position and having a projection formed thereon adapted to lie within the opening in the first mentioned wing portion whereby the second mentioned wing portion is caused to bulge away from the central body portion 30 into a three-dimensional form when the body portion is bent into a three-dimensional form, one of said lateral wing portions having a slot formed therein, an additional wing portion overlapping said central portion when in collapsed position and adapted to lie within said slot whereby the additional wing portion is moved 35
- 40

info a predetermined plane at an angle to the first mentioned wing portion when the body portion is bent into a three-dimensional form.

16. An article of the character described comprising a body member formed of stiff sheet material adapted to be bent into a three-dimensional form and having an opening therein, a wing member hingedly connected to said body member and having a tab normally lying in said opening and extending through said opening 10 when said body member is bent, means on said tab for engaging the body member when in bent form to lock said body member in bent form, said body member being provided with an opening suitable for the insertion of the finger of an operator above the level of the engagement of the tab with the body member for facilitating erecting the article.

17. An article of the character described comprising a body member formed of stiff sheet material adapted to be bent into a three-dimensional form and having an opening therein, a wing member hingedly connected to said body member and having a tab normally lying in said opening and extending through said opening 20 when said body member is bent, means on said tab for engaging the body member when in bent form to lock said body member in bent form, said body member being provided with an opening suitable for the insertion of the finger of an operator below the level of the engagement of the tab with the body member for facilitating collapsing the article when in erected form.

18. An article of the character described comprising a body member formed of stiff sheet material adapted to be bent into a three-dimensional form and having an opening therein, a wing member hingedly connected to said body member and having a tab normally lying in said opening and extending through said opening 30 when said body member is bent, means on said tab for engaging the body member when in bent form to lock said body member in bent form, said body member being provided with a plurality of openings adapted to receive fingers of an operator for facilitating erecting and collapsing the article, one of said openings being above the level of the engagement of the tab with the body member, and another of said openings being below said level.
